UNITED STATES PATENT OFFICE.

JAMES W. COLLIER, OF NEW YORK, N. Y.

INCANDESCENT-ELECTRIC-LAMP SOCKET.

SPECIFICATION forming part of Letters Patent No. 409,929, dated August 27, 1889.

Application filed June 10, 1889. Serial No. 313,676. (No model.)

To all whom it may concern:

Be it known that I, JAMES W. COLLIER, of the city, county, and State of New York, have invented certain new and useful Improvements in Sockets or Holders for Incandescent Electric Lamps, of which the following is a specification.

The socket or holder in which my invention is comprised is one made of hard rubber or equivalent insulating material—that is to say, a material which is a non-conductor of electricity and is capable of being molded into form. Into this holder, by and during the operation of forming or molding the holder, are molded and embedded all of the contacts and fixed circuit-connections, in this way dispensing with the screws and other appliances and fittings heretofore used for securing in place these parts. The holder has a socket proper for reception of the neck of the lamp, and a chamber for reception of the metallic cam or switch-piece by which the circuit through the holder is controlled, said chamber and socket being formed on opposite sides of a permanent non-conducting diaphragm or partition formed in one with the body of the holder. The switch or cam-receiving chamber is closed by a cap through which the current-conducting wires pass, said cap being removable and serving not only as a means by which the holder can be attached to a supporting-bracket and by which the switch-chamber is sealed, but also as a means whereby the conducting-wires, without other instrumentality, may be clamped in place into secure connection with their respective contacts in the holder. At the point where the stem of the key passes through the side of the holder there is preferably a stuffing-box by which the stem is tightly packed, so as to prevent entrance of outside air or moisture into the switch-chamber, the whole arrangement and organization being such that the working parts of the holder are to all intents and purposes hermetically inclosed in the holder out of the reach of extraneous influences by which they might be injuriously affected and by which their electrical efficiency might be impaired.

A holder such as I have above described in a general way can be used safely and without deterioration in localities—as, for exam-

ple, in the moist and highly-heated atmosphere of "Turkish" or "Russian" baths, so-called—where the ordinary incandescent lamp-holders of to-day soon become incapacitated for useful service. Moreover, the holder is most simple in its construction. All of the fixed contacts and connections are embedded and molded into the body of the holder, so that they and the body are absolutely in one to all intents and purposes, while the only additional mechanical part to be added is the switch or circuit-controlling cam, which by simple means can be so arranged that it may readily be taken out whenever it becomes necessary to replace or repair it. In fact, the only metallic pieces visible in the holder are the contact-surfaces themselves and the circuit-controlling switch or cam-piece.

The nature of my improvement will readily be understood by reference to the accompanying drawings, in which—

Figure 1 is an external view of the holder. Fig. 2 is a longitudinal central section of the same in the plane of the switch or circuit-controlling cam. Fig. 3 is a similar section in a plane at right angles to the plane of section of Fig. 2. Fig. 4 is an end view of the cap end of the holder with the cap removed.

The body A of the holder is made from a plastic non-conducting material, but preferably is hard rubber. It is molded with a lamp-socket a, a cam-receiving chamber b, and an intermediate diaphragm or partition c, which is in one with the remainder of the body of the holder.

The lamp-contacts are shown at d d', the switch or cam contacts at e e', and the contacts for the current supplying or conducting wires at f f'. Contacts d e are connected electrically by connecting-strip g, contacts d' f by connecting-strip h, and contacts e' f' by connecting-strip i. All of these contacts and connections are molded and embedded in the holder during the operation of forming the latter, and by the subsequent vulcanizing they are most firmly and permanently held on the body of the holder, no part of them being exposed save the mere contact-surfaces themselves.

Chamber b is closed and sealed by a cap B, also of vulcanite or hard rubber, which screws on the chamber end of the holder. Through

a central aperture *j* pass the insulated conducting-wires *k* to their respective contacts *ff'*. In order to provide a convenient and sure connection, I prefer to make the contacts *ff'* tubular, as shown. The wires *k* are bent, as indicated, and after being passed through the cap (not yet applied to the holder) their bent ends are inserted each in its tubular contact-socket *f* or *f'*. The cap is then 10 screwed onto the holder, and in screwing it down into place the annular internal shoulder *l*, with which it is formed, will press upon and clamp the wires most securely in place, as indicated in Fig. 2. The cap serves as 15 a means by which the holder can be secured in place, and to this end its aperture *j* is screw-threaded and made of size and dimensions to fit the standard stem employed in the electric-light fixtures of to-day.

20 Inasmuch as the cap is to screw both upon the stem of the fixture and upon the holder and wires therein, means must be provided for preventing the wires from being twisted during these operations. To this end, inasmuch as the aperture *j* must have a right-hand screw-thread in order to fit the standard screw-threaded bracket or supporting-stem now generally used, the end of the cap which screws upon the holder has a left-hand 25 screw-thread. In this way the cap can be screwed upon its supporting-stem and the holder simultaneously, and by the time it has clamped the wires it has been screwed sufficiently upon its supporting-bracket.

30 The metallic cam or switch piece *C* may be of any suitable construction or form. In the position shown it has closed the circuit between the contacts *e* and *e'*. By giving it a quarter-turn from the position the circuit will be 35 interrupted. This circuit-controlling cam has in its center a square hole to receive the squared inner end of the key *D*, which passes through a bearing in the side of the holder. The key, when engaged with the cam, is held 40 in that position by a tongue *m*, sliding in a guideway formed for it in the body of the holder and entering an annular groove *n* in the stem of the key. By withdrawing the tongue the key can be drawn out and the cam 45 50 (which is really the only movable part in the holder and the only piece of metal appertain-

ing to it which is not embedded in the hard rubber) can readily be removed and replaced.

At the point in the side of the holder where the key passes through into the cam-receiving chamber I prefer to provide a stuffing-box *p*, which surrounds and packs the stem of the key to prevent entrance into the chamber of moisture or other corroding or oxidizing agent, which might injure the efficiency 60 of the switch-cam.

Having described my improvements and the manner in which the same are or may be carried into effect, what I claim as new and of my own invention is—

1. The non-conducting holder having the socketed main-wire contacts *ff'* and their permanent connections molded and embedded within its body and provided with the non-conducting cap *B*, as and for the purposes 7c hereinbefore set forth.

2. The non-conducting holder having the socketed main-wire contacts *ff'* and their permanent connections and provided with the non-conducting right and left screw-cap *B*, 75 adapted at once and by the same movement to clamp the main or leading-in wires into place and to screw upon the bracket or support for said socket, as set forth.

3. An incandescent lamp-holder, of hard 80 rubber or equivalent non-conducting material, formed in one piece, containing a lamp-socket, and a switch-receiving chamber solidly partitioned from said socket and having molded and embedded in it the fixed contacts for the 85 lamp, switch, and main or leading-in wires, together with the permanent connections between said contacts, and provided with a movable circuit-controlling switch or cam piece in said chamber, a key-stem extending through 90 the side of the holder into said chamber and detachably engaged with both the holder and the cam-piece, and a removable cap for closing the rear end of the switch-receiving chamber, as set forth.

In testimony whereof I have hereunto signed my name this 8th day of June, A. D. 1889.

JAMES W. COLLIER.
